UNITED STATES PATENT OFFICE.

STERLING A. MILLARD, OF CLAYVILLE, NEW YORK.

SCYTHE-BLADE.

SPECIFICATION forming part of Letters Patent No. 227,033, dated April 27, 1880.

Application filed December 31, 1879.

To all whom it may concern:

Be it known that I, STERLING A. MILLARD, of Clayville, in the county of Oneida and State of New York, have invented a new and Improved Scythe-Blade, of which the following is a specification.

Figure 1 is a side elevation of the blade. Fig. 2 is an enlarged vertical sectional elevation on line $x x$, Fig. 1. Fig. 3 represents a modification of the shape of the blade.

Similar letters of reference indicate corresponding parts.

The object of this invention is to provide a scythe-blade that, containing much less weight of metal, shall possess equal or greater strength than the ordinary scythe-blades. The scythe-blade is made in the usual manner from what is termed by scythe-makers a "scythe-rod," and is wrought and shaped in such form that a proper thickness is left to serve as the back of the blade, which thickness or rib is relied upon by scythe-manufacturers to give the required lateral stiffness to the blade; but this back rib rarely gives the necessary lateral flexibility or stiffness to the blade, and also fails to afford sufficient resistance to torsional strain.

My invention consists in constructing a scythe-blade with a longitudinal auxiliary rib or supplementary back, which forms an obtuse angle transversely with the flat inner or cutting portion of the blade, and also with the flat web that intervenes between said rib and the back proper, whereby the scythe is stiffened to the requisite degree without requiring the same weight of metal as those of the usual construction.

In the drawings, A indicates the flat inner cutting portion of the scythe, and a and b , respectively, the back rib proper and the supplementary or auxiliary back. The latter is formed by the angle of the flat cutting portion or blade proper, A, and the broad flat web c to each other—that is to say, the part A has a transverse inclination of about fifteen degrees to the part c , so that the rib b has an obtuse angle with relation to both.

This construction has been found to yield an important result—namely, it enables a scythe-blade to be made very light at the same time that it is rendered very stiff and strong, so that it will resist the torsional strain incident to use, which result is practically a desideratum of first importance.

In rare instances—as when unusual strength is required—I may form one or more small lengthwise corrugations in the middle of the web c , as shown in Fig. 3.

What I claim is—

As a new and improved article of manufacture, a scythe provided with a longitudinal rib or supplementary back, b , which has an obtuse angle to the flat cutting portion A and to the flat web c , which joins the back proper, a , said blade being also at a transverse angle to the web, as shown and described, for the purpose specified.

STERLING A. MILLARD.
